UNITED STATES PATENT OFFICE.

HARRY B. ROUSE, OF CHICAGO, ILLINOIS, ASSIGNOR TO H. B. ROUSE & CO., OF CHICAGO, ILLINOIS, A CORPORATION OF ILLINOIS.

PRINTING-FORM-ALINING APPARATUS.

1,133,822.

Specification of Letters Patent. Patented Mar. 30, 1915.

Application filed February 11, 1914. Serial No. 817,975.

To all whom it may concern:

Be it known that I, HARRY B. ROUSE, citizen of the United States, residing at Chicago, in the county of Cook and State 5 of Illinois, have invented a certain new and useful Improvement in Printing-Form-Alining Apparatus, of which the following is a full, clear, concise, and exact description, reference being had to the accompanying 10 drawings, forming a part of this specification.

My invention relates to printing and has for its object the provision of improved means for imposing page forms in the printing form of which the page forms are component parts. In practising my invention I preferably employ bars at the sides of the 15 imposing plate, riders upon the bars, and strings upon the riders, the strings serving 20 to mark out rectangular locations defining the location of the page forms. As the invention is preferably practised the riders are provided with clamps to secure them in their adjusted positions upon the bars which 25 carry them. These riders are desirably provided with slots for holding the strings.

These features and other characteristics 30 of my invention will be fully described in connection with the accompanying drawings showing the preferred embodiment of my invention and in which—

Figure 1 is a plan view illustrating an imposing plate, a form thereon, and the equipment of my invention in position; Fig. 2 is a view in end elevation taken partially in 35 section on line 2 2 of Fig. 1; Fig. 3 is a view of a part of the structure as it appears in Fig. 1, on a larger scale, and with a measuring tool shown in addition; Fig. 4 is a sectional view on line 4 4 of Fig. 1; Fig. 5 is a perspective view of a component 40 part of the equipment; and Fig. 6 is a view of a measuring device that may be used in adjusting the equipment.

Like parts are indicated by similar characters of reference throughout the different figures.

The imposing plate 1 is supported in any preferred or usual manner, as upon the top 50 of a printer's cabinet 2. Bars 3 are secured to the sides and ends of the imposing plate by means of screws 4, the tops of these bars being shown as closely approximating the level of the form that is imposed upon the 55 plate 1. This form is shown as being com-

posed of a number of printing plates 5 mounted upon wooden blocks 6 to make them type high, each plate constituting a page form, though it is to be understood that the page forms may be of any desirable 60 nature and construction. The page forms are assembled as usual within a chase 7 and in order that the chase and the form it contains may be readily moved on and off the imposing plate, at least one of the bars 3 is 65 removably mounted to which end the construction illustrated in Fig. 2 may be employed where I have shown down setting slots 8 in the bottom of one of the end bars 3 in which slots the shanks of the screws 4 70 that are employed to secure this particular bar in place are received with sliding fit. By loosening these particular screws this end bar 3 may be moved vertically—upwardly for removing the bar and downwardly for replacing it—the screws 4 belonging to this bar being tightened after the bar has been positioned. For convenience one of the bars 3 upon one of the long sides of the imposing plate may also be thus removably mounted, though it is not desirable 75 to removably mount more than two of such bars.

It will be observed that the screws 4 clamp the bars 3 upon the vertical edges of 80 the plate 1 so that the threaded holes in the plate 1 that are provided for receiving the stems of the screws 4 are formed in the sides of such plate rather than in the top 85 thereof whereby the chase 7 and the form 90 contained therein do not need to ride over the holes that are provided for the screws. I do not wish to be limited, however, to this particular location for the holes. Riders 9 are mounted upon the bars 3, there being 95 as many riders upon each of the longer bars as there are page forms 5 in each long row of page forms in the chase 7 and at least as many such riders upon each of the shorter bars as there are page forms 5 in each short 100 or transverse row of page forms. These riders are preferably provided with clamping or holding means whereby the riders and the bars upon which they are mounted may be secured in the relative positions to 105 which they are adjustably brought by movement of the riders along the bars. The riders are shown as being provided with grooves 10 in their bottom portions for receiving the bars and to have sliding fit 110

therewith, this interengagement of the riders and bars preventing the riders from turning upon the bars, though I do not wish to be limited to this preferred interengagement of the bars and riders for this purpose since other interengaging formations of the bars and riders might obviously be employed. Where the bars are received within the recesses 10 the clamping means, above referred to, are desirably in the form of clamping screws having knurled heads 11 and shanks 12 working in threaded holes that pass from the outside of the riders 9 into communication with the slots or grooves 10 so that the inner ends of the screw stems 12 may have clamping engagement with the bars 3 as illustrated most clearly in Fig. 4.

The riders are provided with slots or grooves 13 that extend at right angles to the slots or grooves 10, there being desirably two slots 13 in the top of each rider adjacent its ends. Thus the slots 13 in the riders upon the long side of the imposing plate 1 are transversely disposed with respect to such plate and the form imposed thereon while the slots 13 in the riders upon the ends of the imposing plate 1 are longitudinally disposed with respect to such plate and form imposed thereon. The adjacent riders upon each of the longer bars 3 are spaced apart a distance equal to the length of a page form 5 plus the distance between this page form and the next page form in the same longitudinal row therewith, or at least this is true of the spacing between slots in these riders. The adjacent riders upon each of the shorter bars 3 are spaced apart a distance equal to the width of a page form 5 plus the distance between this page form and the next page form in the same transverse row therewith. The slots 13 in the riders carried by adjacent bars 3 are placed in alinement with slots 13 in riders carried by opposite bars 3, the alinement of the slots in the riders carried by one pair of parallel bars 3 being at right angles to the alinement of the slots in the riders carried by the remaining pair of parallel bars 3. Strings 14 are passed through alined grooves 13 so as to extend across the plate 1 and the form imposed thereon whereby a number of rectangular spaces are defined with which the location of the page forms 5 are exactly to correspond so that these page forms will have their relative positions very accurately determined.

It is understood that the chase is first located in its proper position which may be maintained by means of printers' furniture 15 and quoins 16 interposed between the chase and the bars 3. The positions of the page forms 5 within the chase, with respect to each other, and in conformity with the rectangular spaces marked off by the strings

14 are determined in the usual way by means of printers' furniture 17 and quoins 18.

The relative positions of the imposing plate 1 and the bars 3 are determined by means of the screws 4 and the threaded holes 70 that receive their stems and which are preferably provided in the sides of the imposing plate 1. A permanently fixed block or projection 19 is mounted adjacent one end of each bar 3 to provide markers upon the different bars that are in fixed relation with respect to each other and with respect to the imposing plate 1, these markers being used in properly locating the riders 9 upon their bars. The markers 19 are provided with slots 13¹ whereby the positions of these markers may be determined with respect to each other, with the aid of strings entering the slots, before the markers are made fast to the bars which carry the same. The slots 85 13¹ in the blocks 19 at opposite sides of the plate 1 are in alinement and the alinement of such slots in one pair of opposite blocks is at right angles to the alinement of such slots in the other pair of opposite blocks. 90

In order to space the riders 9 with respect to each other and with respect to the blocks 19 these riders and blocks are provided with registering formations, preferably cylindrical, which are preferably in the form of 95 holes 20 at the middle portions of the blocks 9 and 19. These registering formations are used in conjunction with a measuring tool in accurately determining the spaces between each marker 19 and the rider 9 next adjacent thereto and between adjacent riders. Where holes 20 are employed in the tops of the elements 9 and 19 the measuring tool illustrated in Figs. 2, 4 and 6 may be employed, this measuring tool having a pin 21 fixed at one 105 end and a pin 22 which is carried upon a rider 23 movable upon a measuring beam 24, the adjusted position of the pin 22 being secured by means of a clamping screw 25. By means of the measuring instrument shown 110 the spacing between the pins 21 and 22 may be made to conform first to the spacing that is to exist between the hole 20 in the block 19 upon a bar 3 and the hole 20 in the rider 9 next adjacent the block in order accurately 115 to determine the spacing between such block and rider, it being understood that the rider 9 is shifted until the pins 21 and 22 may be received in the holes 20. After the first rider 9 upon its bar 3 has thus been adjusted 120 the first rider 9 upon the opposite bar is similarly adjusted whereafter the position of the pin 22 with respect to the pin 21 of the measuring device illustrated in Fig. 6 is readjusted accurately to equal the spacing 125 that is to exist between the hole 20 of the first rider 9 and the hole 20 of the rider next adjacent thereto, the second rider being adjusted with respect to the first in the same manner in which the first rider was adjusted 130

with respect to the block 19, whereafter the subsequent riders upon the same bar are similarly adjusted with respect to the preceding riders on such bar. The riders upon 5 an opposite pair of bars being thus adjusted, the riders upon the remaining bars are similarly adjusted, though the spacings between the riders upon one set of bars are obviously different from the spacings existing between 10 the riders upon the other set of bars. It is understood that the riders are of similar formation with the holes 20 equidistant between the slots 13. When the holes 20 in adjacent riders 9 upon the shorter bars 3 are 15 spaced apart, as they should be, the distance equal to the width of a page form and the space between this page form and the adjacent page form in the same transverse row therewith, the strings 14, when located in 20 similarly positioned slots 13 in these riders will be correspondingly spaced apart for the purpose which was hitherto expressed. In a similar manner the strings 14 that are engaged with the slots 13 provided in the 25 riders 9 upon the longer bars 3 are spaced apart the distances prescribed for them.

While I have herein shown and particularly described the preferred embodiment of my invention I do not wish to be limited 30 to the precise details of construction shown as changes may readily be made without departing from the spirit of my invention, but—

Having thus described my invention I 35 claim as new and desire to secure by Letters Patent the following:—

1. The combination with an imposing plate; of a plurality of string supporting riders at each of the upright sides of the imposing plate, the imposing plate having supporting means for the riders along which the riders may move; and means for fixedly securing the riders in position with respect 40 to the imposing plate, said riders being provided with cylindrical formations whereby they may coöperate with a measuring instrument having corresponding formations in establishing the spacings between the 45 riders, there being also cylindrical formations in permanently fixed relation to the 50

imposing plate to act as markers in positioning the riders.

2. The combination with an imposing plate; of a plurality of string supporting riders at each of the upright sides of the 55 imposing plate, the imposing plate having supporting means for the riders along which the riders may move; and means for fixedly securing the riders in position with respect to the imposing plate, said riders being provided with measuring formations whereby they may coöperate with a measuring instrument having corresponding formations in establishing the spacings between the 60 riders.

3. The combination with an imposing plate; of a plurality of string supporting riders at each of the upright sides of the imposing plate, the imposing plate having supporting means for the riders along which 70 the riders may move, the riders and said supporting means having interengaging formations whereby the riders are prevented from turning materially; and means for fixedly securing the riders in position with 75 respect to the imposing plate.

4. The combination with an imposing plate; of a plurality of string supporting riders at each of the upright sides of the imposing plate, the imposing plate having supporting means for the riders along which 80 the riders may move, the riders and said supporting means having interengaging formations whereby the riders are prevented from turning materially.

5. The combination with an imposing plate; of a plurality of string supporting riders at each of the upright sides of the imposing plate, the imposing plate having supporting means for the riders along which 90 the riders may move; and means for fixedly securing the riders in position with respect to the imposing plate.

In witness whereof, I hereunto subscribe my name this ninth day of February A. D., 95 1914.

HARRY B. ROUSE.
